UNITED STATES PATENT OFFICE.

HENRY R. NELSON, OF WALNUT GROVE, MINNESOTA.

FASTENING DEVICE FOR RUBBERS.

No. 892,760.

Specification of Letters Patent.

Patented July 7, 1908.

Application filed April 12, 1907. Serial No. 367,749.

To all whom it may concern:

Be it known that I, HENRY R. NELSON, of Walnut Grove, Redwood county, Minnesota, have invented certain new and useful Improvements in Fastening Devices for Rubbers, of which the following is a specification.

In walking over a muddy road or street, the over shoe or rubber will frequently stick in the mud and be pulled off the shoe as the 10 foot is lifted in the act of walking.

The object of my invention is to provide means for securing the rear portion of the rubber or overshoe to the shoe to prevent its being accidentally pulled off.

15 The invention consists generally in various constructions, and combinations, all as hereinafter described and particularly pointed out in the claims.

In the accompanying drawing, forming 20 part of this specification, Figure 1 is a view of the foot and ankle showing the rubber or overshoe on the shoe with the foot raised in the act of taking a step, my invention being illustrated in place on the shoe. Fig. 2 is 25 an edge view of the clamp. Fig. 3 is a rear view showing the clamp closed. Fig. 4 is a similar view showing the clamp open. Fig. 5 is a sectional view on the line $x-x$ of Fig. 3. Fig. 6 is a detail view showing curve in 30 the jaws to conform them to the curve of the rubber. Fig. 7 is a sectional view on the line $y-y$ of Fig. 3. Figs. 8 and 9 are detailed views of the clip or fastening device by means of which the loose end of the string is 35 secured.

In the drawing, 2 represents a shoe and 3 a rubber or overshoe. 4 and 5 are jaws, preferably of metal loosely secured together by a pivot pin 6. The jaw 4 is preferably 40 provided with a series of teeth 7 on its lower edge. The upper end of the jaw 4 has an eye 8 formed therein and a cam 9 that is adapted to engage the jaw 5 and force the ends of the jaws apart and cause their lower edges to be 45 moved toward one another to grip any material that may be inserted between them. If the edges are swung to the position indicated in Fig. 4, there will be sufficient movement permitted to the jaw 5 on the pivot pin 50 to allow the upper edge of the counter por-

tion of the rubber to be inserted between the edges and then when the jaw 5 is swung to the position indicated in Fig. 3, the edge of the rubber will be gripped and firmly held. The jaw 5 also has an eye 10 and a string 11 is threaded through the eyes 8 and 10 and is of sufficient length to extend around the ankle and the upper of the shoe.

55 A plate 12 is attached to one end of the string and is provided with oppositely arranged spring tongues 13, under which the free end of the string is inserted and drawn taut and held securely by the tongues until it is desired to remove the device from the foot. The plate with the spring tongues 60 permits the clamps to be easily and quickly put in place on the shoe or removed therefrom without the necessity of tying or untying a knot.

65 I do not wish to be confined to the particular form of clamping jaws illustrated herein as the same are capable of modification and still have substantially the same functions and other means may be employed for securing the loose end of the string without departing from the spirit of my invention.

70 I claim as my invention:

1. A fastening device for rubbers comprising pivotally connected jaws having curved lower edges to conform to the curve of 75 the rear portion of the rubber, one of said jaws having a series of teeth, a cam mounted on one of said jaws and adapted to engage the other to force the lower edges together and a string attached to said jaws and adapted to extend around the ankle, substantially as described.

2. A fastening device for rubbers, comprising disk-shaped jaws 4 and 5 centrally pivoted together and having curved lower 80 edges, one of said curved lower edges having a series of teeth and said jaws having projections with eyes or loops formed therein, one of said jaws having a cam surface to engage the projection on the other jaw and hold them in their clamping position, and a cord passing through said eyes or loops and adapted to be secured around the ankle, substantially as described.

3. A fastening device for rubbers, com- 100

prising jaws centrally pivoted together and having lower edges between which the edge of the rubber is inserted, one of said jaws being adapted to swing in a plane parallel substantially with the plane of the other jaw and one jaw having a cam edge to engage the other jaw, whereby they will be held in their locked position, and means attached to said

jaws and extending around the ankle, to secure the device to the foot.

In witness whereof, I have hereunto set my hand this 6th day of April 1907.

HENRY R. NELSON.
